(73) Assignee: **Griffin Technology, Inc.**, Nashville, TN (US)

(57) **CLAIM**

(**) Term: **14 Years**

The ornamental design for a case with stand for an MP3 player device, as shown and described.

(21) Appl. No.: **29/272,875**

DESCRIPTION

(22) Filed: **Feb. 20, 2007**

FIG. 1 is a perspective view of the case with stand for an MP3 player device showing our new design and wherein the stand is moved to a stored condition;

(51) **LOC (8) Cl.** **14-03**

FIG. 2 is a bottom view thereof;

(52) **U.S. Cl.** **D14/217**; D14/496; D3/218

FIG. 3 is a top view thereof;

(58) **Field of Classification Search** D14/496,

FIG. 4 is a front view thereof;

D14/217, 432, 434, 474, 168, 224, 299; D3/218,

FIG. 5 is a back view thereof;

D3/318, 201, 273; D6/407; 455/1, 95, 100;

FIG. 6 is a left side view thereof;

224/908, 929; 206/307, 307.1, 305, 387.1;

FIG. 7 is a right side view thereof;

379/908; 345/156, 162, 905; 463/46, 47

FIG. 8 is a perspective view of the case with stand of FIG. 1 wherein the stand is moved to a condition for supporting the case in an upright condition;

See application file for complete search history.

FIG. 9 is a top view thereof;
